US00D760289S

(12) **United States Design Patent**
Kendler et al.

(10) **Patent No.:** **US D760,289 S**
(45) **Date of Patent:** **** Jun. 28, 2016**

(54) **DISPLAY SCREEN OF A SYRINGE PUMP WITH A GRAPHICAL USER INTERFACE**

(71) Applicant: **DEKA Products Limited Partnership**,
Manchester, NH (US)

(72) Inventors: **Jonathan Kendler**, Utrecht (NL);
Jonathan I. Tilliss, Somerville, MA
(US)

(73) Assignee: **DEKA Products Limited Partnership**,
Manchester, NH (US)

(**) Term: **14 Years**

(21) Appl. No.: **29/477,237**

(22) Filed: **Dec. 20, 2013**

(51) LOC (10) Cl. **14-04**

(52) U.S. Cl.

USPC **D14/492**; D14/493

(58) **Field of Classification Search**

USPC D14/485-495

CLAIM

The ornamental design for a display screen of a syringe pump with a graphical user interface, as shown and described.

DESCRIPTION

The FIGURE is a front view of display screen of a syringe pump with a graphical user interface, showing the new design.

The broken lines of a syringe pump and portions of the graphical user interface form portions of the article and form no part of the claimed design.
